SWIMMING DEVICE
Barney B. Gorden, North Stonington, Conn.
(R.D. 1, Norwich, Conn.)
Filed Aug. 1, 1962, Ser. No. 213,950
7 Claims. (Cl. 9—309)

This invention relates to a swimming device, and more particularly to a swimming device for propelling the body through water, such as fins or the like, which will provide a neutral buoyancy to the legs of a swimmer.

Swimming devices, particularly those worn on the feet, such as fins, are quite widely used by aquatic sportsmen and others engaged in water pursuits. It is quite well known that the legs and feet of a swimmer have a negative buoyancy in water. Therefore it becomes necessary for a person to overcome such negative buoyancy to learn how to swim to keep his feet from sinking.

It is therefore an object of the present invention to provide improved swimming devices which are attached to the feet of a swimmer to propel the body through the water yet which will overcome the negative buoyancy of the feet.

Another object of this invention is the provision of a device in conjunction with conventional swimming fins adapted to provide neutral buoyancy to the legs of a swimmer to enable the swimmer to maintain a stable equilibrium in any position in the water, thus allowing the swimmer to stay in a position of rest when desired for prolonged periods, whether the swimmer is in a swimming or floating position.

In accomplishing the foregoing and other objects of the present invention there is provided a buoyant material, impervious to water, which is incorporated in the conventional fin so as to form a unitary device therewith. The buoyant material may be secured to and form a part of the fins at any convenient point or portion thereupon without affecting the driving power of the fin. The amount of buoyant material calculated to assist the swimmer and to provide a neutral buoyancy is of course dependent upon the material used, and physical stature of the person employing the device according to the present invention.

Other and further objects and advantages of the present invention will be apparent to those versed in the art from the following description of the invention as illustrated in the accompanying drawings in which like characters refer to like parts in the several views, and in which:

FIG. 1 is a view in perspective of the present invention attached to the feet of a swimmer;

FIG. 2 is a top plan view of a swimming device showing the buoyant material secured thereto in the sole of the fin;

FIG. 3 is a cross-section taken on line 3—3 of FIG. 2;

FIG. 4 is a side elevational view of a fin showing the position of the buoyant portion at the bottom of said fin;

FIG. 5 is a bottom plan view of the fin as shown in FIG. 4;

FIG. 6 is a view taken on line 6—6 of FIG. 5;

FIG. 7 is a side elevational view of a fin showing the buoyant portion thereof secured to the heel portion of said fin;

FIG. 8 is a longitudinal sectional view of the fin shown in FIG. 7;

FIG. 9 is a side elevational view of a fin having an inflatable member secured thereto to provide buoyancy to said fin; and

FIG. 10 is a longitudinal sectional view of the fin of FIG. 9 showing the inflatable member in an inflated state.

Referring now to the drawings, the swimming device 10 according to the present invention is illustrated in FIG. 1 attached to the foot of a swimmer, and comprises a heel

2

portion 11, joined to a sole portion 12 which is provided with a forwardly extending fin portion 13. A hollow foot pocket 14 having a convex curvature extends from the left to the right sides of the sole portion 12 and is provided with an orifice 15 at the forward end of the sole portion 12. The fin portion 13, which is relatively flat, may be provided with tapered sides 16 extending from the region of the instep to the forward end of the fins 13 so as to form a substantially hollow undersurface 17 in the area along which said sides 16 extend.

The swimming device 10 is further provided with a buoyant member 20 assuming the configuration of and secured to the sole 12 as illustrated in FIGS. 2 and 3. Said buoyant member 20 is fabricated of a water-imperious material preferably of an expanded polyethylene foam having an extremely low water absorption and absorption factor. The amount of material necessary to provide the buoyancy required is of course dependent upon the particular material used, and the distribution of buoyancy in the body of the person employing the device of the present invention. In this connection, it has been found that a $\frac{3}{4}$ pound buoyancy is required for the average child and 3 pounds for a large adult, with a 2 pound buoyancy factor considered average for the average adult individual.

As has heretofore been indicated, placement of the buoyant material may be conveniently secured to the fins at any area of the swimming device except where it might interfere with the driving power of the fin. As illustrated in FIGS. 4-6, the buoyant member 25 is secured along the hollow undersurface 17 of the swimming device 10. For protective purposes a coating 26 of rubber or the like is additionally layered thereupon for protective purposes against rough surfaces, especially where the wearer finds it necessary to tread upon such a surface.

The buoyant member 30 may further be appended as by layering or the like to the swimming device 10 as illustrated in FIGS. 7 and 8 so as to be disposed upon the outer surface of the heel portion 11. Securement thereto may be by an appropriate adhesive (not shown) or by means allowing for securement and removability therefrom.

In FIGS. 9 and 10, the buoyant member 35 may be comprised of an inflatable bladder appended to the underportion of the sole portion 12 with means provided for inflating said buoyant member 35 when desired.

Although the present invention has been described with respect to a specific swimming fin structure, it is within the ambit herein that other modifications and changes may be made without departing from the scope of the present invention as described and defined.

I claim:

1. A fin adapted to be mounted on a swimmer's foot comprising:
  - (a) a shoe-like member having a sole, heel and foot receiving pocket;
  - (b) a web-like extension projecting forwardly from said sole of the shoe-like member and being integral with the latter to permit the transmission therethrough of substantial propulsive forces; and
  - (c) a cellular buoyant member permanently secured to said shoe-like member so as to avoid interference with the transmission of said propulsive forces through said web-like extension to the water, said buoyant member contributing sufficient buoyancy to said fin to overcome the negative buoyancy of the leg of a swimmer having its foot received in said pocket.
2. A fin as in claim 1; wherein said buoyant member is of a water-imperious expanded polyethylene foam material on the outside of said shoe-like member.

3. A fin as in claim 2; wherein said buoyant member underlies said sole of the shoe-like member.

4. A fin as in claim 2; wherein said buoyant member extends around said heel of the shoe-like member.

5. A swimming device adapted to be mounted on a 5 foot comprising:

(a) a heel portion;

(b) a sole portion joined to said heel portion and extending forwardly therefrom;

(c) a fin portion extending forwardly from said sole 10 portion;

(d) a foot receiving pocket formed over said sole portion;

(e) a pair of vertical side members extending down- 15 wardly from both sides of said sole portion to form a hollow portion thereunder;

(f) a buoyant member secured within said hollow portion, and

(g) a protective layer enveloping said buoyant member.

6. A swimming device adapted to be mounted on a 20 foot comprising:

(a) a heel portion;

(b) a sole portion joined to said heel portion and extending forwardly therefrom;

25

(c) a fin portion extending forwardly from said sole portion;

(d) a foot receiving pocket formed over said sole portion;

(e) a pair of vertical side members extending down- wardly from both sides of said sole portion to form a hollow portion thereunder, and

(f) buoyant means secured within said hollow portion.

7. A swimming device according to claim 5; wherein said buoyant member is fabricated of a water-impervious expanded polyethylene foam material.
